UNITED STATES PATENT OFFICE

102,143

DESIGN FOR A TILE UNIT

Eugene Parker, Los Angeles, Calif.

Application January 13, 1936, Serial No. 60,544

Term of patent 7 years

To all whom it may concern:

Be it known that I, Eugene Parker, a citizen of the United States, residing at 1525 North Formosa Avenue, Los Angeles, in the county of Los Angeles, State of California, have invented a new, original, and ornamental Design for a Tile Unit, of which the following is a specification, reference being had to the accompanying drawing, forming part thereof.

Figure 1 is a front elevational view of a tile unit showing my new design;

Figure 2 is a side elevational view thereof.

I claim:

The ornamental design for a tile unit, substantially as shown.

EUGENE PARKER.
